ATTORNEY

UNITED STATES PATENT OFFICE

WILLIAM G. SHELTON, OF ST. LOUIS, MISSOURI

HAIR WAVER

Application filed September 27, 1928. Serial No. 308,638.

My invention relates to hair curling or waving equipment and consists in a novel device for holding a strand of hair while heat is applied to the same during the waving operation.

One of the objects of my invention is to provide a simple, light, efficient member for gripping the strand of hair adjacent to the scalp of the user and mounting the curling and heating elements which will protect the user from contact with the heater or from contact with steam or hot water resulting from the liquid applied to the hair during the waving operation.

Another object of my invention is to provide, in a device of the class described, structure for readily wrapping the hair about a curling rod, and holding the strand tightly in wrapped position and facilitating the application of a moistened pad to the wound strand of hair.

Another object of my invention is to provide simple and effective means for quickly engaging and disengaging the hair gripping elements and the hair and for quickly engaging and disengaging the heater element and the hair gripping elements.

In the accompanying drawings which illustrate a selected embodiment of my invention—

Figure 1 is an end elevation of the assembled structure.

Figure 2 is a side elevation of the same.

Figures 3 and 4 are vertical sections on lines 3—3 and 4—4 of Figures 2 and 1, respectively. Figure 3 also shows a strand of hair and treating pad.

Figure 5 is a horizontal section on line 5—5 of Figure 4 showing the hair gripping elements separated.

Figure 6 is a detail view of one of the curling rod mounting elements.

The scalp of the user is indicated at S and T is a strand of hair, a number of which will be manually formed and have individual heaters applied thereto. The strand T will be gripped adjacent to the scalp by a pair of bars 1 and 2 hinged to each other at one end, as indicated at 3, and forming the base of the device. These bars are preferably formed of

Bakelite, or other suitable insulating material, and preferably will be grooved along their bottoms, as indicated at 4, to lighten the same and to provide air passages adjacent to the scalp. I show the meeting faces of bars 1 and 2 provided with a recess 5 and a projection 6, respectively. Preferably, the projection 6 will be of a separate element of sponge rubber, or the like, secured in a recess in bar 2 and will be provided with transverse grooves 7 throughout a portion or all of its length to hold the strand of hair in fairly even distribution, thereby keeping the strand flat. Catch elements 8 and 9 are provided on the unhinged ends of bars 1 and 2, the same forming an eccentric device for adjustably clamping the bars together.

Bars 1 and 2 are provided with upstanding ends 10 and a curling or waving rod 11 is positioned between these ends and is journaled thereon by elements 13 and 16. The stud 13 is provided with a knurled knob 15 whereby it may be gripped by the fingers of the operator and positively rotated in the base together with rod 11. The split pin 16 is seated in a recess formed in the opposite end of rod 11 and is provided with a flattened outer end 17 which engages the sides of the slot 18 formed in the corresponding base end 10. It will be understood that the inner end of pin 16 is formed of spring material and yieldingly engages the sides of the recess in rod 11 to frictionally resist rotation of the rod on the base so as to hold the rod against unwinding, due to elasticity of the hair, although not interfering with more positive rotation of the rod by the hand. The rod is provided with a spring clip 19 for engaging the outer end of the strand of hair to be wound thereon.

The heater element includes a semi-circular shell 20 formed of insulating material and adapted to fit over rod 11 and a strand of hair wound thereon and this shell 20, with base bars 1 and 2, forms a complete enclosure for the hair and rod. Suitable electric resistance elements are mounted in shell 20 and a body 21, attached thereto and are connected by wires 22 with a source of electrical supply. These elements and their as-

sembly with the shell, in themselves, form no part of my invention. A member for attaching the shell to the base is indicated at 23 and preferably consists of a flat strip having ends 24 adapted to be seated in suitable recesses 25 formed in the outer faces of ends 10. Preferably, at least one of the ends of member 23 will be of spring material so as to permit quick attachment and 10 detachment of the heater device.

To apply the device to a strand of hair, the base will be applied to the inner end of the strand, the bars 1 and 2 being clamped together by the elements 8 and 9; the curling rod 11 will be applied to the outer end of the strand and the rod turned, thereby winding the rod down to the base, the stud 13 and pin 16 being received in the recesses provided therefor in ends 10 and the non-circular end of pin 16 and its frictional engagement with rod 11 preventing unwinding of the rod and strand. Near the end of this winding operation, a moistened pad 26 will be applied to the strand and wound 25 with the same during the last convolution or so. This pad is an article of which there are a number of different types in use, a simple form comprising a sheet of flannel or blotting paper, or both, combined with a sheet of foil. However, the form of this pad, or its use at all, is immaterial to my present invention. By means of stud 13, the winding of the strand on the rod may be tightened to any desired extent and it is unnecessary to apply any holding means. After the winding of the strand is completed, the heating device is quickly applied by snapping the ends 24 of member 23 into the recesses 25 provided therefor on the base. 30 In the event of illness of the customer, or other emergency, the heaters may be almost instantaneously separated from the remainder of the apparatus by unsnapping the yielding end or ends 24 from the base ends 45 10.

It is obvious that many of the details of my invention may be varied without departing from the spirit thereof, and I contemplate the exclusive use of all modifications 50 thereof which come within the scope of my claims.

I claim:

1. In a device for a hair waver, a pair of arms of insulating material hinged to each other at one end and adapted to grip a strand of hair between them and having faces for resting on the scalp of a user and provided with recesses forming air passages adjacent to the scalp when the waver is in use, and 60 means at their other end for holding them together.

2. In a device for a hair waver, a pair of arms of insulating material hinged to each other at one end and adapted to grip a strand 65 of hair between them, and having recesses in

their scalp engaging faces extending from end to end to permit the passage of air between the same and the scalp, and means at their other end for holding them together.

3. In a device for a hair waver, members for gripping a strand of hair between them, upstanding elements on the ends of said members, a rod about which said strand may be wrapped, the end portions of said rod being recessed, a stud secured in one of said recessed ends and journaled in one of said elements and projecting therefrom and having a head by which said stud and rod may be rotated, and a split pin seated in the other of said recessed ends and frictionally engaging the sides of its recess and non-rotatively seated in the other of said elements.

4. In a device for a hair waver, a base including means for gripping a strand of hair near the scalp of the user, upstanding end elements on said base, one of said elements having a slot extending inwardly from its outer edge, a rod positioned between said ends and having a recess in the end portion adjacent to said slotted element, and a pin split lengthwise throughout a portion of its length with its split portion expanded and inserted in said recess and with its unsplit portion being non-circular in shape and seated in said slot and engaging the sides thereof.

5. In a device for a hair waver, members for gripping a strand of hair between them and provided with upstanding ends, a rod seated in said members and about which rod said strand may be wrapped, a heater device cooperating with said members to enclose said rod and a strand of hair thereon between said ends, and a quickly detachable spring element on at least one of said ends and said device for holding the same in assembled relation.

6. In a device for a hair waver, members for gripping a strand of hair between them and provided with upstanding ends having outwardly facing recesses, a rod seated in said members and about which rod said strand may be wrapped, a heater device cooperating with said members to enclose said rod and a strand of hair thereon between said ends, and catch elements on the ends of said device for entering said recesses, at least one of said catch elements being of spring material to provide quick and easy assembly and disassembly of said device and members.

In testimony whereof I hereunto affix my signature this 21st day of September, 1928.

WILLIAM G. SHELTON.
